UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,350,725.

Specification of Letters Patent. Patented Aug. 24, 1920.

Application filed July 15, 1919. Serial No. 310,934.

To all whom it may concern:

Be it known that I, MONROE GUETT, a citizen of the United States, residing at Hartford, in the county of Hartford and State of Connecticut, have invented certain new and useful Improvements in Electric Switches, of which the following is a specification.

This invention relates to electric switches. A switch involving the invention can be employed with advantage in many different connections; for instance, it may form a part of the equipment of a vacuum cleaner or sad-iron, these being merely two of several illustrations. I have several motives in view, among them being the provision of an article of the character set forth, which can be easily mounted and readily operated.

In the drawings accompanying and forming part of the present specification, I have shown in detail a form of embodiment of the invention, which to enable those skilled in the art to practice the same will be set forth in detail in the following description. I am not necessarily restricted to this particular showing; I may depart therefrom in several respects within the scope of the invention defined by the claims following said description.

Referring to said drawings:

Figure 1 is a top plan view of the switch.

Fig. 2 is a longitudinal central section of the same, taken on the line 2—2 of Fig. 1, looking in the direction of the arrows.

Fig. 3 is a central transverse section on the line 3—3 of Fig. 1, looking in the direction of the arrows.

Fig. 4 is a horizontal practically central section on the line 4—4 of Fig. 2, also looking in the direction of the arrows.

Like characters refer to like parts throughout the several views.

In Letters Patent No. 1,254,223, granted to me January 22, 1918, and to which reference may be had, is shown a switch possessing some of the attributes of that covered hereby. The patented switch is, as will be understood, highly advantageous, yet the present switch accomplishes results not possible by that of the patent.

The switch involves in its construction a case as 2, which as shown, is of cylindrical form, although this is not necessarily a

primary consideration. The top of the case is denoted by 3 and it is practically in form 55 of a metal disk, having diametrically opposite ears or lugs 4 which match the off-standing lugs 5 at the upper end of the body of the case. Overlaying this top 3 is a cover or face plate 6, through perforations 60 in which and also in the respective lugs 4 and 5, screws as 7 extend, the screws being in threaded engagement with the respective lugs 5 and acting as a convenient means to hold the top 3 and face plate or cover 6 in 65 position. The face plate or cover has in addition holes or perforations as 8 adapted to receive screws or equivalent means by which the switch as a unit may be fastened to a 70 support.

The switch involves a circuit-controlling or switching member. This circuit-controlling or switching member obviously has "on" and "off" positions. When the circuit controlling or switching member is in the 75 "on" relation it extends between and electrically bridges contacts or terminals of suitable nature, a form of which is shown and will hereinafter be described. A circuit-controlling member such as meets my 80 condition is designated by 9 and as represented, is in the form of a metal piece such as an eyelet set in and extending through a carrier as 10. This carrier 10 is practically in the form of a segment, having two 85 straight top surfaces as 11 and 12. The segment 10 is shown as having extending practically centrally from the upper end thereof, the upstanding arm manipulating portion 13. The arm and the segmental 90 carrier 10, as illustrated, are integral with each other, the base of the arm, or where it unites with the carrier is rounded somewhat to present a hub portion 14, and through the same extends the pivot pin 15. 95 This hub portion 14 as I have termed it, extends through registering openings 17 in the top 3 and face plate 6 respectively, the pin lying in grooves or depressions 18 extending laterally from the wall of the lower 100 opening. The carrier 10, the actuator or arm 13 and the hub portion 14 are flat, or at least it is desirable that their opposite faces should be, and they are made usually in one piece from some insulating material. 105 The eyelet 9 is headed through the carrier

10, at one side of the perpendicular central line of the carrier, there being at a practically similar distance on the opposite side of the line, a hole or opening 19 which is 5 plain or non-eyeletted.

There are disposed against the lower and upper surfaces of the bottom of the case 2 disks as 20 and 21 of some insulating material having registering holes through 10 which and through holes in the bottom of the case, the studs 22 and 23 extend, these studs as shown, being interiorly threaded to receive screws as 24 by which wires or like conductors may be electrically connected to the studs. Said holes in the bottom of the case are larger than the eyelets or studs 22 and 23 to prevent short circuiting. The terminals of the switch are designated by 25 and 26 respectively each being practically, of L or angular shape. The forked horizontal portions of the terminals, fit under the upper flange of the studs 22 and 23. The upright portions of the terminals 27 and 28 which face inward to co-operate 25 with the metallic eyelet or rivet 9 or hole 19. In full lines in Fig. 2 and also Figs. 3 and 4, the switching or circuit closing member 9 is supposed to be in the operative or "on" position, the bosses 27 and 28 at this time fitting in the metallic eyelet 9. To reverse the switch, the actuator 13 is swung over to the dotted line position in Fig. 2, thus moving the eyelet 9 away from the bosses 27 and 28, the motion being continued until the 35 bosses can be projected into the hole 19.

The case 2 interiorly thereof is furnished with projections as 29 and 30 arranged in pairs, and which can be formed by pressing the metal or other stock of the case inwardly. The space or interval between the respective pairs of projections is practically equal to the width of the carrier 10. The carrier, as will be understood, is alternately projected into these spaces, as shown 45 for instance by full and dotted lines in Fig. 2.

What I claim is:—

1. An electric switch comprising a case provided with a cover having an opening, a segmental carrier of insulating material 50 in the case, having an arm integral therewith, the arm extending through the opening in the cover, a pivot projecting through the segmental carrier, at its junction with the arm, the cover having grooves extending 55 oppositely from the opening, and the pin being set in said grooves to thus permit oscillation of the carrier by said arm, contacts in the case, and a switching member on the carrier, the arm as it rocks causing the 60 switching member to move between and in

engagement with the contacts and then out of such engagement.

2. An electric switch comprising a case provided with a cover having an opening, a segmental carrier of insulating material 65 in the case, having an arm integral therewith, the arm extending through the opening in the cover, a pivot projecting through the segmental carrier, at its junction with the arm, the cover having grooves extending 70 oppositely from the slot, and the pin being set in said grooves to thus permit oscillation of the carrier, a rivet supported by the carrier and constituting a switching member, the arm as it rocks causing the rivet to move 75 between and in engagement with the contacts and then out of such engagement.

3. An electric switch comprising a case provided with a cover having an opening, a flat segmental carrier of insulating material 80 in the case, having a flat arm integral therewith, the arm extending through the opening in the cover, contacts in the case, a switching member on the carrier, a pin projecting through the segmental carrier at its 85 junction with the arm, the cover having grooves extending oppositely from the opening, and the pin being set in said grooves to thus permit oscillation of the carrier by 90 said arm, the arm as it rocks causing the switching member to move between and in engagement with the contacts and then out of such engagement, and a face plate set against the cover, having an opening through which 95 said arm passes, and means for uniting the face plate and the cover to each other and for also uniting both parts to the case.

4. An electric switch comprising a case provided with a cover having an opening, a flat segmental carrier of insulating material, 100 in the case, an operating arm for the carrier, rigidly associated therewith and extending through said opening in the cover, a pivot connected with the segmental carrier approximately at its junction with said arm, the cover having means to support the pivot 105 and thus permit oscillation of the carrier by said arm, contacts in the case, and a rivet supported by the carrier and constituting a switching member, the arm as it is rocked 110 causing the switching member to move between and into engagement with said contacts and then out of such engagement.

In testimony whereof I affix my signature in the presence of two witnesses.

MONROE GUETT.
